[57] ABSTRACT

This disclosure is concerned with a novel electrical terminal structure embodying insulative clamping members having cooperative interlocking tubular extensions securing a thin housing or similar support wall and a component-mounting heat-sink plate sandwiched therebetween, and with the upper clamping member being provided with recess means for receiving and locking therein the head of a terminal post passed through the tubular members.

ELECTRICAL TERMINAL STRUCTURE

The present invention relates to electrical terminal structures, being more particularly concerned with the application of such structures to thin-walled housings or chassis mountings and the like that are to support heat-sink-mounted electrical components and similar structures.

The art is replete with numerous types of electrical terminal constructions and mounting structures for heat sinks and related apparatus, ranging from nuts and bolts to soldered lugs, brackets, eyelets, and a host of complicated fastening devices. The complexity of assembly and disassembly and the time for effecting the same are increasingly important factors, however, in low-cost mass production of many systems; and in certain applications, such as thin-walled housings for engine ignition circuits and the like, which may be potted and which expose only terminal ports or connectors, the ease of alignment of the posts, the assembly thereof, and the security against loosening are particularly of concern.

A useful prior terminal unit for some of such applications is disclosed, for example, in my prior United States Letters Patent No. 3,359,530, involving a grooved insulating member for receiving a contact pin adapted to receive a contact member, and inner and outer plate-like members for the insulating member provided with tabs connected thereto. There are instances, however, where the terminals are to be disposed near electrical components mounted upon a flat, heat-sink plate or the like that is to be juxtaposed with a thin-walled housing, and where such prior constructions would still necessitate separate plate-mounting structures and securing devices. There are also applications where small size and minimum securing devices are advantageous. It is to the solution of the problem of providing a unitary structure that not only supports the terminals but also enables the same simultaneously to act as the securing members for the heat-sink or similar structures, and with minimal size, number of components and time of required assembly, that the present invention is thus primarily directed.

A further object of the invention is to provide a new and improved self-aligning and clamping electrical terminal structure of more general applicability also.

Other and further objects will be explained hereinafter and are more particularly delineated in the appended claims.

In summary, the invention contemplates a self-aligning and clamping electrical terminal structure for mounting upon a thin conductive housing wall and the like having, in combination, cooperative-flat insulative clamping members one of which is provided with upwardly projecting hollow tubular means of a predetermined outer diameter and the other of which is provided with downwardly projecting hollow tubular means of a slightly greater diameter for fitting over to interlock with the upwardly projecting hollow tubular means, with the latter of length sufficient to pass through and extend somewhat beyond aligned somewhat greater-diameter aperture means in each of a thin housing wall and a thin juxtaposed conductive component-mounting heat-sink plate sandwiched between the clamping members, the said other clamping member having flanged locking recess means on its upper surface for receiving and locking against rotation

the correspondingly shaped head of a conductive electrical terminal provided with post means projecting downwardly through the hollow tubular members and the interposed wall and plate and provided with securing means at the free end thereof for holding the structure together.

The invention will now be described with reference to the accompanying drawing, the single FIGURE of which is an expanded isometric view of a preferred construction illustrated prior to the assembly of the elements thereof to show the details thereof.

Referring to the drawing, a thin conductive wall of a housing or the like is shown at 1, upon which a conductive flat heat-sink plate 2, as of copper, is to be mounted in juxtaposed relationship (in some applications, with a thin insulation sheet 3 interposed, such as a thin polyimide film or the like), the plate carrying electrical components such as solid-state devices 4 the housings of which are mounted in contact with the upper surface of the plate 2 to be radiation-cooled thereby.

In accordance with the invention, terminal connectors 5 are to be insulatingly mounted near this structure, the terminals being illustrated as comprising flat rectangular heads 5' and having threaded depending posts 5'' and integrally bonded or otherwise provided electrical leads 5''' extending upwardly therefrom in the drawing. The structure above the wall 1 may be potted, as is required in the ignition circuit and similar applications before discussed. Through the use of novel cooperative insulating clamping members, as of plastic, shown as an upper unitary member 6 and a lower member 7, the terminals may themselves not only be readily aligned in their desired positions, but they may also simultaneously serve to align and secure the complete assembly 1-3-2-5, as well, and prevent rotation.

To effect this, the lower clamp 7 is provided with a pair of hollow tubular members upwardly projecting from the flat bottom portion thereof at 7', while the upper clamping member 6 has corresponding downwardly extending hollow tubular projections 6' of slightly different (e.g., greater) diameter for fitting with the tubular members 7' in interlocked fashion. Prior to such reception, the member 7 is applied to the lower surface of the wall 1 with the tubular members 7' inserted within aligned similar holes or apertures 1', 3' and 2' of the respective members 1, 3 and 2, of just slightly greater diameter than the outer diameter of the tubular members 7'. The length of the tubular members 7' is sufficient to extend somewhat above the heat-sink plate 2 so as to enable facile assembly of the structure 55. The upper clamping member 6 is then applied with the depending tubular members 6' thereof interlocking with the tubular members 7' to complete the assembly, with the housing wall 1, insulator sheet 3 (if used) and juxtaposed heat-sink mounting plate 2 sandwiched between the clamping members 6 and 7.

The upper clamping member 6 is provided along its flat upper surface with flanged rectangular recesses 6'' of just greater dimensions than the flat correspondingly rectangular heads 5' of the terminals 5 such that, when the threaded posts 5'' are inserted through the tubular members 6' and 7' (that insulate the same from any possible contact with the surfaces 1 and 2), the heads

5' become received within the recesses 6" and are thereupon locked against rotation, providing relatively large-area clamping surfaces as well. Threaded nuts 8 on the free ends of the posts 5" extending beyond the bottom surface of the lower insulating clamp member 7, enable ready tightening of the clamped assembly, exposing only these free ends below the wall 1.

While rectangular heads 5' are preferred, other configurations providing rotation-preventing geometry may also be used, as may other modifications be effected without departing from the spirit and scope of the invention as defined in the appended claims.

What is claimed is:

1. A self-aligning and clamping electrical terminal structure mounted upon a thin conductive housing wall or the like having, in combination, cooperative-flat insulative clamping members one of which is provided with upwardly projecting hollow tubular means of a predetermined outer diameter and the other of which is provided with downwardly projecting hollow tubular means of a slightly different diameter for fitting and interlocking with the upwardly projecting hollow tubular means, with the latter of length sufficient to pass through and extend somewhat beyond aligned somewhat greater-diameter aperture means in each of said thin housing wall and a thin juxtaposed conductive component-mounting heat-sink plate sandwiched between the clamping members, the last other clamping member having flanged locking recess means on its

upper surface receiving and locking against rotation the correspondingly shaped head of a conductive electrical terminal provided with post means projecting downwardly through the hollow tubular members and the interposed wall and plate and provided with securing means at the free end thereof for holding the structure together.

2. A terminal structure as claimed in claim 1 and in which a thin insulative sheet is sandwiched between 10 said plate and housing wall and is provided with aperture means corresponding to and aligned with the plate and housing wall aperture means.

3. A terminal structure as claimed in claim 1 and in which each of said tubular means, aperture means and 15 locking recess means comprises a spaced pair of such means.

4. A terminal structure as claimed in claim 1 and in which the said locking recess means and the terminal head are of similar rectangular configuration, with the 20 latter of slightly smaller dimensions than the former in order lockingly to fit therein.

5. A terminal structure as claimed in claim 4 and in which the head is provided with a connected electrical lead extending upwardly therefrom.

25 6. A terminal structure as claimed in claim 1 and in which the downwardly projecting tubular means is of slightly greater diameter than the upwardly projecting tubular means.
